(57) **CLAIM**

The ornamental design for a handle of a foldable saw, as shown and as described.

DESCRIPTION

FIG. 1 is a perspective view of a handle of a foldable saw showing my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view thereof, wherein the broken line showing of the blade is for illustrative purposes only and forms no part of the claimed design.

1 Claim, 6 Drawing Sheets

FIG. 2

FIG. 3

FIG. 5

FIG. 4

FIG. 6

FIG. 7

FIG. 8
